Thomas A. Gatten

BY *Fred Gatten* ATTORNEYS

UNITED STATES PATENT OFFICE.

THOMAS ALBERT GATTEN, OF BRAINERD, MINNESOTA.

MOLDER'S TROWEL.

1,244,487.

Specification of Letters Patent.

Patented Oct. 30, 1917.

Application filed February 7, 1917. Serial No. 147,139.

To all whom it may concern:

Be it known that I, THOMAS A. GATTEN, residing at Brainerd, in the county of Crow Wing, and State of Minnesota, have invented a new and Improved Molder's Trowel, of which the following is a specification.

My invention has reference to improvements in trowels and other like tools and particularly molder's trowels.

10 As is well known to those skilled in the art to which my invention relates, a molder while at work must of necessity see down into the mold, and as most foundries are pretty dark, he generally uses a hand mirror for reflecting light down into the mold.

This method of "lighting" the mold is not satisfactory at times, on account of not being able to catch the light right and also on account of requiring the use of one hand for

20 holding and directing the mirror while using the other hand for manipulating the trowel.

In using a molder's trowel, it is usual for the workman, while gripping the handle, to use the index finger for holding the blade 25 down on the work.

My invention has for its purpose to provide a tool of the character stated with a flash light attachment so mounted in the handle, that at the desired times, the workman, while maintaining the required grip 30 on the handle and the index finger pressure on the blade may conveniently turn on or off the flash light with the third or the little finger of the hand that grasps the tool.

35 My invention also has for its object to provide in a flash light attachment for tool holders, means for so maintaining the flash light devices in the bore of the handle, that the light rays are directed from the outer 40 end of the handle, and in which the battery is held under proper tension to maintain the required position when adjusting the light holder to close contact with the battery terminal and for holding the battery from fol-

45 lowing up the light socket or holder, when the latter is adjusted out of contact with the said battery and for preventing the battery from dropping out of the handle socket when the light holder or socket is detached 50 therefrom.

With other minor objects in view that will hereinafter appear, my invention consists in a flash light attachment for tool handles, that embodies the peculiar features of construction and novel arrangement of the parts

to be hereinafter explained, specifically pointed out in the appended claims and illustrated in the accompanying drawings, in which:

Figure 1 is a perspective view of a molder's trowel equipped with my improved flash light attachment, the latter being shown in the active position.

Fig. 2 is a side elevation thereof, the flash light devices being shown as adjusted to the closed or active position.

Fig. 3 is a longitudinal section of the complete handle and the flash light attachment, the latter being shown at the closed or active position.

Fig. 4 is a longitudinal section of the outer end of the handle and the attachment, the lamp being shown at the normal or cut out position.

Fig. 5 is a cross section taken on the line 75 5—5 on Fig. 3.

In carrying out my invention, the tool handle 1, preferably wooden, is formed with a longitudinal bore or socket 2 that extends nearly the length of the handle, the outer portion 20 of which is enlarged for receiving the lamp socket, while the inner portion 2 is of sufficient depth for holding a dry battery of any of the well known types used for flash lights.

85 In my construction of flash light attachment, the main socket portion 2 is provided with a metallic liner 3, the base 30 of which seats against the inner end of the said socket 2, while the outer end is extended as at 30°, 90 and projects into the outer socket portion 20, the reason for which will presently appear.

4 designates a liner of insulated material within the metal liner 3 and 5 designates a dry flash light battery of any of the well known types, which is removably held within the insulated liner and is projected to its normal or outermost position by a coil spring 6 at the inner end, which forms a contacting element for engaging the negative pole of 100 the battery and the metal liner 3, as is clearly shown in Fig. 3, by reference to which, it will be also observed that the outer or projected end of the liner 3 is cut with one or more tongs 31 that are bent inwardly, after 105 the battery is inserted, and forms stops to hold the battery from being projected beyond a fixed or operative point, it being understood that when the battery runs out, that by bending back the said tongs 31, the 110

worn battery may be readily slid out of the end of the handle and a new one substituted therefor.

7 designates a metal liner for the socket end 5 20 and it has internal threads 70 for receiving the threaded surface 80 of the lamp socket 8 in which the lamp 9 and the lens 90 are mounted.

It will be noticed, by referring to Figs. 3 10 and 4, that the lamp socket is formed with a tubular extension 81 that forms a contact member which slidably engages the extension 30^a of the metal liner 3, the latter and the socket extension 81 being relatively such 15 that under either the open or closed adjustment of the socket 8, contact between the said members 81 and 30^a is maintained.

51 designates the opposite pole of the battery 5 with which the lamp 9 contacts and 20 closes the circuit when the lamp socket is moved inwardly to the closed position, as is clearly shown in Fig. 3.

By reason of mounting the lamp devices 25 in the manner described and shown, the workman, as he grasps the trowel in the usual manner (see Fig. 1) while working, can readily turn the lamp socket with the third or little finger and close the circuit to produce the flash light, since but a single 30 turn of the socket may be sufficient to move the socket to the position shown in Fig. 3, it being obvious that the said lamp socket may be likewise turned to cut out the lamp, the said two operations being, as stated, 35 effected with the hand working the tool, it being understood that the battery is maintained at all times in proper position for being engaged by the contact on the lamp, to provide for a proper closure of the circuit, which passes from the negative end 40 of the battery through the spring to the metal liner 3, from the said liner to the lamp socket, through the lamp and from the lamp to the positive end of the battery.

45 From the foregoing description taken in connection with the drawings, the complete construction, the manner of operation and the advantages of my invention will be readily apparent.

50 The arrangement of the flash light device is such that the light rays are not interfered with by working the tool, and the light can be thereby easily directed to the right spots in the mold, this being made 55 possible by flashing the light from that end of the handle farthest from the blade.

While I have shown the tool handle shaped for holding but one battery and flash light for projecting the light from one end 60 of the handle, it is obvious that the handle may have both ends shaped for receiving a set of flash light devices for each end of the handle.

What I claim is:

65 1. A flashlight attachment for tool han-

dles which includes a battery held on the handle, a lamp socket, said socket having a rotatable endwise feed connection with the handle for effecting the opening and closing of the light circuit, the said endwise feed connection being arranged to be operated by the hand while holding the handle and manipulating the tool.

2. A flash light attachment for tool handles comprising in combination with a handle having a longitudinal socket or bore that includes an inner portion of one diameter and an outer portion of larger diameter, a metallic liner for the smaller socket portion, said liner including an extension projected into the enlarged portion of the bore, an insulating liner within the metallic liner, a battery removably held within the insulated liner, a coil spring that forms a circuit closing element, the said spring bearing at 75 one end on one pole of the battery and at the other end against the inner end of the metal liner and operating to exert tension pressure on the battery to hold it out of its active position, a stop device that engages the outer end of the battery and holds it from being projected out of the handle socket, an internally threaded metallic liner in the outer enlarged end of the handle socket, a lamp socket having a threaded portion for engaging the threaded liner and a hub-like extension for slidably engaging the extension of the metallic liner in the inner end of the handle socket, a lamp in the lamp socket, said lamp having a contact for engaging the adjacent contact of the battery.

3. A flash light attachment for tool handles comprising in combination with a handle having a longitudinal socket or bore that includes an inner portion of one diameter and an outer portion of larger diameter, a metallic liner for the smaller socket portion, said liner including an extension projected into the enlarged portion of the bore, an insulating liner within the metallic liner, a battery removably held within the insulated liner, a coil spring that forms a circuit closing element, the said spring bearing at one end on one pole of the battery and at the other end against the inner end of the metal liner and operating to exert tension pressure on the battery to hold it out of its active position, a stop device that engages the outer end of the battery and holds it from being projected out of the handle socket, an internally threaded metallic liner in the outer enlarged end of the handle socket, a lamp socket having a threaded portion for engaging the threaded liner and a hub-like extension for slidably engaging the extension of the metallic liner in the inner end of the handle socket, a lamp in the lamp socket, said lamp having a contact for engaging the adjacent contact of the battery, said stop device consisting of tongs bend-

able from the extended end of the metallic liner in the handle socket and adapted for being projected over the outer end of the battery.

- 5 4. A flash light attachment for tool handles comprising in combination with a handle having a socket or bore extending from one end thereof, the said bore including an outer enlarged end and an inner reduced 10 end, a metal liner for the reduced end, the said liner including an extension that projects into the enlarged end of the bore, an insulating liner within the metallic liner, a battery removably held within the inner 15 bore section, a spring located between the

inner end of the battery and the metal liner that contacts with one pole of the battery and the said metal liner, an internally threaded liner for the enlarged end of the bore, a lamp socket including a threaded shank for 20 fitting the said socket, the said lamp socket including an inwardly extending hub that slidably engages the extended end of the metallic liner and a lamp in the socket having a contact for engaging the adjacent battery contact, the said socket including a turning element located outside of the socketed end of the handle. 25

THOMAS ALBERT GATTEN.
